US0D1080193S

(12) United States Design Patent (10) Patent No.: US D1,080,193 S
(45) Date of Patent: * Jun. 24, 2025

(54) BACKPACK

(71) Applicant: Dongyuan (Guangzhou) Trading Co., Ltd., GuangZhou (CN)

(72) Inventor: Yongmei Ke, HuiZhou (CN)

(73) Assignee: Dongyuan (Guangzhou) Trading Co., Ltd., GuangZhou (CN)

() Term: 15 Years

(21) Appl. No.: 29/987,517

(22) Filed: Jan. 24, 2025

(51) LOC (15) Cl. 03-01

(52) U.S. Cl.

USPC D3/217
